UNITED STATES PATENT OFFICE

2,485,493

UNITARY BED BOTTOM AND MATTRESS
STRUCTURELouis Jacobs, Chicago, Ill., assignor to Jerome S.
Weiss, Chicago, Ill.

Application June 30, 1944, Serial No. 542,896

1 Claim. (Cl. 5—285)

This invention relates to beds and has for its particular object to provide a bed structure which will take the place of the customary bed frame, springs and mattress and in a single, integral structure answer the purposes of those three articles.

A further object of the invention is to provide an integral bed structure which may be handled and reversed to expose two different sides to use.

A further object of the invention is to provide an integral bed structure of this character in which the coil springs are resiliently suspended from the structure frame.

These and other features of the invention will be seen from the following detailed specification read in connection with the accompanying drawings forming part thereof and in which—

Fig. 1 is a perspective view of the bed structure of this invention with one corner thereof cut away to show the organization of the coil spring assembly suspended within the frame and the manner of application of the padding;

Fig. 2 is a perspective view of the frame member; and

Fig. 3 is a fragmentary section of one side of the pad structure taken on the line 3—3 of Fig. 1.

Referring to the drawings, the bed structure comprises a frame 11 which is made in the form of two longitudinal frame members 12 and two transverse frame members 13 which together form a rectangular frame. This may be fabricated from metal, wood, or other suitable material. The entire frame is flanged with the horizontal flanges 15 on top and bottom and is equipped at each of the corners with a bracket 14 by which the frame may be attached to and supported by the headpiece and footpiece of the bed or, if desired, separate bed posts. The frame thus eliminates the need of the usual frame members of the bedstead.

Within the frame 11 a coil spring assembly 21, which is made up of conventional coil springs 23 secured together and fastened within the border wire 22, is suspended on the helical springs 20 which are secured to the border wire 22 and to the frame flanges 15 through the holes 19 in the flanges.

As shown in Fig. 3, the coil spring assembly extends above and below the frame flanges 15 but is suspended within the frame by means of the helical springs 20.

In the preferred embodiment shown in the drawings, the coil spring assembly is covered by a fabric covering 24 which may be made of duck

or other suitable fabric, drawn tautly over the coil spring assembly by means of the retainer springs 25.

The entire frame and coil spring assembly are then covered by an outer padding which may be composed of one or a plurality of layers of suitable padding material such as cotton, felt, hair, or other conventional mattress materials.

The padding may be made of one material, for example cotton, on one side of the bed structure, as indicated at 26, and a different material, such as hair, on the other side 27. The material is covered with suitable mattress cover material well known in the art.

15 The brackets 14 which fasten to each corner of the frame, as shown in Fig. 1, protrude through the covering materials so that the entire bed structure may be attached to head and footpieces or to bed posts without any alteration or disturbance of the various parts of the bed structure.

20 To facilitate the handling of the bed structure suitable handles 16 are retractably secured to the bed frame 11, as shown in Fig. 2, and if desired these may be provided with light handle springs 17 to insure retraction of the handles when they are not needed. These handles project through the covering, as shown in Fig. 1.

25 The bed frame may be provided with vents 18 which lead to vents 29 in the padded covering so that as the bed structure is in use the movement of the sleeper upon the bed structure will circulate air through the bed structure.

If desired, roll 28 may be formed on both the upper and lower edges of the mattress. Roll 28 may suitably be formed by securing portions of the mattress cover material around cording, or the like.

The manner of use of the bed structure is readily manifest from the foregoing description.

30 Having thus shown and described one embodiment of the invention, it is to be understood that it is capable of many modifications. Changes, therefore, in the construction and arrangement may be made without departing from the spirit and scope of the invention as disclosed in the appended claim.

I claim:

35 A unitary bed bottom and mattress structure adapted to be mounted on a bedstead head member and foot member comprising a rigid rectangular bed frame, a coil spring assembly unit including a plurality of coil springs mounted in a wire border, a plurality of springs secured to the wire border and rigid rectangular frame for suspending the coil spring assembly unit in the rigid

rectangular bed frame, a padded covering completely enclosing and padding the rectangular bed frame and the coil spring assembly unit suspended therein, and brackets carried by the rigid rectangular bed frame projecting through the 5 padded covering and having attaching means thereon to mount the unitary bed bottom and mattress structure on the bedstead head member and foot member.

LOUIS JACOBS. 10
